UNITED STATES PATENT OFFICE.

GEORGE WALTER CRANDALL, OF PLATTSMOUTH, NEBRASKA.

ELECTRIC TORCH FOR WELDING, BRAZING, AND CUTTING.

Application filed March 29, 1926. Serial No. 98,058.

My invention relates to electric torches, and has to do more particularly with apparatus of the above character adapted for welding, brazing and cutting, my improved 5 torch being adapted for all of the above uses.

An object of my invention is to provide a portable electric torch of the above character which is simple in construction, positive 10 in operation, easy to apply and light in weight.

For a better understanding of my invention reference is to be had to the accompanying drawing, in which—

15 Fig. 1 is a side elevation of my improved torch; and

Fig. 2 is a top plan view of the upper carbon holding bracket straightened out to more clearly show the construction of the 20 various parts.

Referring now more in detail to the construction employed, I provide a suitable handle which is preferably in the form of a tubular member A of insulating material 25 such as fibre, but of a substance that will not be affected by the heat from the arc. This handle A is bored throughout its length, the lower end 5 being large enough to take two conductors 6—7, with conductor 6 passing 30 out of an opening 8 bored through the side of the handle so said conductor may be extended to the carbon. The single remaining conductor 7 extends up through the smaller bore 9 and out of the end of the 35 holder to the upper carbon. The member A has its lower end shaped so that it may be readily grasped in the hand by the operator in using and applying the torch.

For holding the carbons I preferably provide two similar brackets, each adjustable so that it not only may be adjusted along the handle A, but angularly adjusted according to the length of the carbon and the work it is being employed on. Referring to 45 the upper bracket, for its construction I provide a clamping member 10 which encircles the handle and may be fastened by the clamping nut 11 so that the bracket may be raised and lowered on the handle. The arm 50 of this bracket 10 carries a carbon holder 12 which is pivotally attached to bracket 10 and adapted to be clamped thereto by the clamping bolt and nut 13. The outer end 55 of bracket 12 encircles the carbon 14 and has a clamping screw and nut 15 whereby the electrode carbon may be adjusted in the

clamping end of the holder 12 to adjust the carbon as it reduces in length. In order to apply the current connection closest to the arcing end of the carbon, and prevent 60 the carbon holder 12 from becoming hot, I provide a terminal clamp 16 which fastens around the carbon 14 and to which the conductor terminal 17 is applied. This terminal clamp 16 is rotatable on the carbon 14 65 so that it may be swung around into any position to clear the work to which the torch is being applied. By the bracket construction employed the carbons may be adjusted into any angle so that the arcing ends project out clear of the device and may be 70 readily applied to the work, whether it is welding, brazing or cutting. The lower carbon carrying bracket is preferably similar to the upper one, but is also connected 75 to a finger lever or trigger 18, so that the carbon may be manipulated or adjusted to form the arc. This finger lever 18 is preferably of an insulating material and is connected through a link 19 to the carbon 80 bracket 12' so that as the trigger 18 is moved toward and away from the handle 5, the carbon points are correspondingly adjusted. Thus to adjust the device 85 to secure the arc, the lever 18 is first pushed outwardly to close contact between the two electrode carbons and then lever 18 is slowly pulled toward the handle A to separate the points of the carbon the proper distance to form the desired arc. 90 To break the arc the trigger is pulled back to separate the carbon points sufficiently to 95 interrupt the circuit.

In the use of the device, the positive wire 7 is connected to the positive feed wire on 95 the arc welding machine and the negative wire 6 from the torch and the negative feed wire from the main are clamped onto the metal table on which the work is placed while being operated upon, so the current 100 flow is from negative through positive and into the metal table.

What I claim as new and desire to secure by United States Letters Patent is:—

1. A portable electric torch of the character described including a handle, a pair of adjustable electrode carbon holders insulatingly supported by the handle and having clamping elements to encircle the carbon to hold the latter at an intermediate point, a 110 carbon held in each of said holders at an intermediate point, a conductor terminal

clamped around each carbon intermediate its held point and the arcing end, and conductors suitably held by the handle and connected with the terminals.

- 5 2. A portable electric torch of the character described including a handle, a pair of adjustable electrode carbon holders insulatively supported by the handle and having clamping elements to encircle the carbon to 10 hold the latter at an intermediate point, a carbon held in each of said holders at an intermediate point, a conductor terminal clamped around each carbon intermediate its held point and the arcing end, said terminals 15 being circularly adjustable around the carbon so as to clear the work being operated upon, and conductors suitably held by the handle and connected with the terminals.
3. A portable electric torch comprising a 20 handle, electrode holders insulatively supported thereon, electrodes carried thereby, electricity conductors passing through the handle and extended laterally thereof and disposed in opposed relation to constitute 25 terminal clamp supports, and terminal clamps carried thereby and engaged with the electrodes.

4. A portable electric torch comprising a

handle, electrode holders insulatively supported thereon, electrodes carried thereby, 30 electricity conductors passing through the handle and extended laterally thereof and disposed in opposed relation to constitute terminal clamp supports, and terminal clamps carried thereby and engaged with the 35 electrodes and arranged for axial adjustment about the electrodes to clear the work.

5. A portable electric torch having a tubular handle, a pair of brackets supported by the handle, an electrode carbon holder supported by each bracket, one of said holders being pivotally supported by its bracket, a bell crank lever pivoted at its mid-point to the tubular handle, one arm of the bell crank having a connection to the pivotally 40 supported holder and the other arm of the bell crank having an aperture for receiving the finger of an operator for adjusting the position of the carbon holder, a conductor terminal clamped around each carbon intermediate its held point and the arcing end, and conductors supported by the handle and connected with the terminals.

In witness whereof, I hereunto subscribe my name this 20th day of February, 1926.

G. WALTER CRANDALL.
